DRYING PRESS

Carl E. Becker, Camden, N. J.

Application May 18, 1931. Serial No. 538,369

5 Claims. (Cl. 18—17)

This invention relates to an improved press for use particularly in the manufacture of artificial teeth although in its broader aspects the press may be used in the production and primary heat treatment of various products made from ceramic materials.

It is a primary object of the present invention to provide a multiple press capable of simultaneously holding in rigidly assembled clamped relationship a plurality of tooth forming molds, wherein each of the molds includes a plurality of separable sections.

It is another object of the invention to provide a press of this character wherein the molds, when situated between the clamping members of the press and in assembled relationship, are subjected to a sufficient degree of heat to effect an initial heat treatment of the articles molded by and in process of formation within the molds.

It is a further object of the invention to provide in connection with the press a fluid cooled table which functions to effect a rapid cooling of the molds following their removal from the heated press to permit of the convenient manual handling of the mold sections in order that the formed articles may be promptly removed and the molds reused for additional and succeeding press operations.

With these and other objects in view, which will appear as the description proceeds, the invention consists in the novel features of construction, combinations of elements and arrangement of parts hereinafter to be more fully described and pointed out in the appended claims.

In the accompanying drawing:

Figure 1 is a front elevation of the mold press formed in accordance with the features of the present invention.

Figure 2 is a vertical transverse sectional view taken on the line 2—2 of Figure 1.

Referring to the drawing by reference characters, the numeral 1 designates my improved press in its entirety. In this instance the press is formed to comprise a supporting bed 2, arranged in a horizontal plane and disposed at a suitable elevation by means of leg members 3. Suitably secured to the upper surface of the bed 2 is the base section 4 of the press, and arising from the base section 4 are spaced vertical sides 5. A top plate 6 rests upon the upper surfaces of the sides 5 and is rigidly secured thereto by the fastening devices 7. The base plate is formed to include a plurality of longitudinally extending substantially V-shaped grooves 8. Each of these grooves is formed to comprise downwardly converging inclined sides 9 and a substantially flat horizontal bottom surface 10. The formation of the grooves 8 is such as to admit of the reception

therein of the lower sections of a plurality of tooth forming molds 11. These molds are preferably of the construction and type disclosed in my co-pending application Serial No. 279,226 filed May 21, 1928 now Patent Number 1,846,012 and wherein each mold includes a pair of complementary lower sections indicated at 12 and 13 which have their outer walls inclined and shaped to correspond with the wall formation of the grooves 8. Also, each mold includes an upper section 14, 65 provided with inclined side walls 15 which engage correspondingly inclined walls 16 provided in longitudinally extending grooves 17 formed in connection with movable press sections 18, hereinafter termed "platens." When the platens are 70 forced downwardly into engagement with the upper portions of the mold sections, as shown in Figure 1, forces are applied to the separable mold sections whereby each mold is firmly secured in an operating position, preventing any relative 75 movement between the sections of each mold.

To effect the vertical movement of the platens into and out of mold engaging positions I employ a rod 19 which has its ends mounted in the sides 5. Rotatably journaled on this rod are a 80 plurality of operating levers 20, one of said levers being provided for each independently removable platen. Pivots connected with an intermediate portion of each lever 20 is a link 21, which has its opposite end connected with a pivot 22 uniting 85 the adjoining ends of a pair of upper and lower toggle links 23. The lower of the links 23 is pivotally connected as at 24 with an eye 25 formed with the upper surface of the complementary platen, whereas the upper end of the upper link 90 23 of each platen is pivotally connected as at 26 with a bolt 27. Each of these bolts is provided with a collar 28 against which rests the lower end of a coil spring 29, the upper end of each of these springs engaging with the upper surface 95 of the top plate 6, while the extreme upper end of the bolt 27 is provided with a nut 30 which is engageable with the upper surface of the top plate 6. With the operating lever in the position disclosed in Figure 2, the spring 29, under compression, forces its platen downwardly into pressing engagement with a mold section, and the spring 29 operates to hold the toggles in their relative aligned position to maintain the pressure on the mold. Of course, other equivalent 100 mechanism may be employed for applying pressure to the molds but the mechanism set forth is preferred in that it is quick to operate and saves the operator's time, as compared with smaller structures, such as the screw operated type set forth in my aforesaid application. A stop strip 31 is secured to the rear side edges of the walls 5 and a corresponding forward strip 32 is secured to the front edges of the sides 5. The strips 31 105 and 32 act as guides and govern the vertical 110 movement of the platens.

travel of the platens. Also, the strip 31 operates as a stop means to limit the rearward position of the molds in the grooves of the press.

The bed 2 and the base section 4 are provided with registering openings 33 and arranged in line with these openings are gas burners or their equivalents 34, which direct the flame upon the molds arranged in the press, whereby said molds and the ceramic articles contained therein, may 10 be heated to a desired temperature simultaneously with the pressing operation.

In conjunction with this structure there is provided a filling table 35. This filling table is of hollow formation and through which a liquid cooling medium may be circulated by means of the ingress and egress 36 and 37 respectively. The upper surface of the table 35 is provided with inclined longitudinally extending grooves 38 which register with the grooves 8 of the press. 20 In operation, the tooth forming molds 11 are initially positioned in the grooves 38 and are separated to permit of the insertion therein of the plastic ceramic materials from which artificial teeth are formed. The mold sections are then 25 assembled and advanced into the press between the base section 4 and the movable platens. The platens are then lowered and brought into clamping and pressing engagement with the molds, holding the latter rigidly against separation or 30 relative displacement. While in the press the molds and the ceramic articles contained therein are subjected to the heat of the burners 34 in order to dry the teeth or other ceramic articles and reduce the same to a dry semipermanent 35 form. When pressed for the proper time the platens are elevated and the molds removed and positioned in the grooves 38 of the filling table. Since this filling table is liquid cooled the heat of the molds is rapidly dissipated so that they 40 may be conveniently handled by the operator. This permits of the substantially immediate separation of the mold sections to effect the removal of the molded teeth and also to permit of the refilling of the molds prior to their subsequent insertion into the press. Any surplus material 45 which may be present on the molds when the latter are initially assembled drops into the outlet space 39 formed between the base section 4 and the filling table 35. A chute 40 registers with 50 the outlet space and drops the surplus ceramic material to an underlying receptacle 41. I preferably provide a plurality of platens which are under the control of a single operator, so that the latter may without loss of time or waste motion 55 successively insert or remove molds into and from the press and yet permit each mold to remain in the press for the required length of time necessary to initially bake, dry or form the ceramic articles to a desired condition.

60 While I have described what I consider to be the preferred form of my improved press, nevertheless it will be appreciated by those skilled in the art that the form of the invention herein described and illustrated exemplifies but one form 65 of my invention and is subjected to considerable variation and modification without departing from the scope of the invention.

What is claimed is:

1. A drying press for manufacturing artificial teeth comprising a stationary base section having a plurality of parallel longitudinally extending grooves, a plurality of selectively movable press sections cooperative with said base section

and provided with grooves registering with the grooves in the base section, said grooves being adapted to receive tooth forming molds, means for heating the molds clamped between said press sections, a filling table arranged laterally of said base sections and in a horizontal plane thereof, said filling table being provided with grooves registering with the grooves in the base section, and means for passing a liquid cooling means through channels formed in said filling table. 85

2. A drying press for manufacturing artificial teeth comprising a stationary base section having a plurality of parallel longitudinally extending grooves, a plurality of selectively movable press sections cooperative with said base section and provided with grooves registering with the grooves in the base section, said grooves being adapted to receive tooth forming molds, means for heating the molds clamped between said press sections, a filling table arranged laterally of said base sections and in a horizontal plane thereof, said filling table being provided with grooves registering with the grooves in the base section, means for passing a liquid cooling means through channels formed in said filling table, 90 said filling table being spaced from said base section to provide a debris removing slot between. 95

3. Apparatus for manufacturing artificial teeth comprising a press structure, means for heating molds positioned in said press structure, 105 and a filling table arranged adjacent to said press structure and provided with means for passing a liquid cooling medium therethrough.

4. Apparatus for molding artificial teeth comprising, in combination, a press provided with relatively movable members having registering mold receiving ways formed in the opposing surfaces thereof, said ways serving to retain the parts of a sectional tooth forming mold in registering relationship when said mold is under compression between the movable members of the press, a substantially horizontal work table arranged laterally of said press members on at least one side thereof, said table being provided with mold receiving ways disposed in longitudinal alignment with the ways of said press members, means for positively heating the molds clamped between said press members, and means for passing a cooling fluid through passages formed in said table to effect and accelerate cooling of the molds positioned in the table ways. 110 115 120 125

5. Apparatus for molding artificial teeth comprising, in combination, a press provided with relatively movable members having registering mold receiving ways formed with the opposing surfaces thereof, said ways serving to retain the parts of a sectional tooth forming mold in registering relationship when said mold is under compression between the movable members of the press, a substantially horizontal work table arranged laterally of said press members on at least one side of said press, said table being provided with mold receiving ways disposed in longitudinal alignment with the corresponding ways of said press members, means for positively heating the molds clamped between said press members, means for effecting a positive cooling of the molds when positioned on the ways of the work table and removed from the region of heat and compression provided by the press members, and an outlet for surplus molding material disposed between said press members and table. 130 135 140 145
